UNITED STATES PATENT OFFICE.

MONTGOMERY BERFIELD, OF VERGAS, MINNESOTA.

GRINDING-MACHINE.

1,143,882.

Specification of Letters Patent. Patented June 22, 1915.

Application filed June 15, 1914. Serial No. 845,309.

To all whom it may concern:

Be it known that I, MONTGOMERY BERFIELD, a citizen of the United States, residing at Vergas, in the county of Otter Tail and State of Minnesota, have invented certain new and useful Improvements in Grinding-Machines, of which the following is a specification.

This invention relates to a grinding machine and the principal object of the invention is to provide a grinding machine which can be used for grinding the knives of farming implements or for any other suitable purpose, such as for grinding the carks of horse shoes.

Another object of the invention is to construct the grinding device that it may be turned at any angle desired when using the same, thus permitting it to be very conveniently used.

Another object of the invention is to provide an improved type of protecting cover for the handle of the grinding machine, the cover protecting the hands of the user and preventing them from being injured or chilled by grasping the cold handle of the grinding machine.

This invention is illustrated in the accompanying drawings, wherein—

Figure 1 is a view showing the grinding machine in elevation; and Fig. 2 is a view showing the grinding machine partially in longitudinal section and partially in elevation.

The grind stone 10 which may be formed of emery or any other suitable material is mounted upon the outer end portion of the shaft 11 and is securely held in place by means of a nut 12 which forces it into tight engagement with the collar 13 of the bearing head 14. This shaft 11 extends through the hollow handle 15 with the beveled face 16 of the bearing head engaging the bearing balls 17 mounted in the cup 18 of the handle. The opposite end portion of the shaft 11 passes through the sleeve 19 which is mounted in the handle 15 and has its outer end portion provided with a head 20 in which there is formed a cup 21 to receive the bearing balls 22. A gear 23 is mounted upon the shaft 11 and is provided with a neck 24, the inner end of which is beveled as shown at 25 to form a bearing surface engaging the bearing balls 22. It will thus be seen that the shaft 11 will be rotatably mounted within the handle and will rest

upon the bearing balls 17 and 22 and be held in spaced relation to the handle 15 and sleeve 19. This will cause the shaft to rotate very freely when the device is in operation.

A driven shaft 26 which is rotated by any suitable means through the medium of a flexible shaft (not shown) extends through a sleeve 27 and is provided with bearing heads 28 and 29 which engage the bearing balls 30 and 31 mounted in the cups 32 and 33 of the sleeve 27. The bearing head 29 forms the neck of the gear 34 which is positioned in the head 35 of the sleeve 27. This head 35 is very similar to the head 20 and is pivotally connected with the same by means of oppositely disposed pins 36 which pass through eyes 37. It should be noted that the heads 20 and 35 are cut off at one side as clearly shown in the drawings so that the handle 15 may be moved at varying angles with respect to the sleeve 27. It should also be noted that the teeth of the gears 23 and 34 will at all times remain in intermeshed relation and that therefore the shaft 11 will be rotated at all times whenever the shaft 26 is rotating.

In order to protect the hands of the operator there is provided a jacket 38 which is formed of leather or any other suitable material and is placed upon the handle with its edge portions overlapping, thus bringing the eyelets 39 into alinement. A lacing 40 is passed through the eyelets 39 as shown in Fig. 2 and holds the jacket in the position shown so that the head 14 of the shaft 11 will be covered, thus preventing any danger of the operator's fingers being injured by coming in contact with this head. In order to securely hold the jacket in the desired position upon the handle there is provided a screw 41 which extends between the leaves 42 of the jacket into the handle with its head engaging the jacket and securely holding the same in place. This protector not only prevents the fingers of the operator from coming in contact with the head 14 but also makes it unnecessary for the operator to take hold of the handle 15 which would be very cold in cold weather.

When in use, the operator grasps the jacket 38 and thus supports the handle so that the handle may be turned at the desired angle and held in the proper position to bring the grind stone 10 into engagement with the cutting edge of the implement

which it is desired to sharpen or into engagement with that portion of any device which it is desired to grind. The shaft 26 which is rotated by any suitable device 5 through the medium of a flexible shaft causes the shaft 11 to rotate through the medium of the gears 23 and 34, thus rotating the grind stone carried by the shaft 11.

What is claimed is:—

- 10 1. A grinding device of the character described comprising a hollow handle, a sleeve mounted in one end of said handle, a head for said sleeve, said sleeve and handle being provided with bearing cups, bearing balls 15 mounted in said cups, a shaft passing through said handle and having one end portion provided with a bearing head engaging the bearing balls mounted in the cup of said handle, a grinding stone carried by 20 the outer end portion of said shaft, a gear carried by the opposite end portion of said shaft within the head of said sleeve and provided with a neck terminating in a bearing face engaging the bearing balls positioned 25 in the cup of said sleeves, a second sleeve having its end portions provided with bearing cups, a head carried by said second sleeve and pivotally connected with the head of said first mentioned sleeve, bearing balls 30 mounted in the cups of said second sleeve, a shaft extending through said second sleeve and provided with a collar having a bearing face engaging the bearing balls in one of the cups of said second sleeve, and a gear 35 carried by said second shaft and meshing with said first mentioned gear and provided with a neck terminating in a bearing surface engaging the bearing balls mounted in the second cup of said second sleeve.
- 40 2. A grinding device of the character described comprising a handle, a sleeve carried by said handle, a second sleeve pivotally connected with said first mentioned sleeve, a shaft rotatably mounted in said handle and 45 said first mentioned sleeve, a second shaft rotatably mounted in said second sleeve, gears carried by said shaft and having their teeth intermeshing to cause rotary motion of said second mentioned shaft to be trans- 50 mitted to said first mentioned shaft, a grinding medium carried by the outer end portion of said first mentioned shaft, a jacket for said handle extending beyond the same and extending about said first mentioned 55 shaft and means for securing said jacket in a desired position upon said handle.
3. A grinding device of the character described comprising a handle, a rotatable shaft extending through said handle, a grinding medium carried by said shaft, a jacket for said handle surrounding the same having its longitudinal edge portions positioned in overlapping relation and provided with registering eyes, a lacing extending through the eyes of said jacket, a set screw 60 passing through said jacket into said handle to hold said jacket in a desired position upon said handle against accidental displacement, and means for rotating said shaft.
4. A grinding device comprising a handle, 70 a rotatable shaft extending through said handle, a grinding medium carried by said shaft, a jacket for said handle, means for connecting the edge portions of said jacket to hold the same about said handle, means 75 for securing said jacket in a desired position upon said handle against accidental displacement, and means for rotating said shaft.
5. A grinding device comprising a handle, 80 a rotatable shaft, mounted in said handle and extending beyond the forward end thereof, a grinding medium carried by the outer end portion of said shaft, and a jacket constructed separate from the handle carried by said handle and extending beyond the forward end thereof and positioned about the outer end portion of said shaft between said handle and grinding medium, and means to prevent longitudinal displacement of the jacket.
6. A grinding device comprising a handle, 85 a sleeve carried by said handle and provided with a head, a driven shaft rotatably mounted in said handle and sleeve, a grinding medium carried by said driven shaft, a gear carried by said driven shaft and positioned within the head of said sleeve, a second sleeve having a head pivotally connected with the head of said first mentioned sleeve, a driving shaft rotatably mounted 90 in the second sleeve, and a gear carried by the driving shaft within the head of the second sleeve and meshing with the gear of said driven shaft.

In testimony whereof I affix my signature in presence of two witnesses.

MONTGOMERY BERFIELD.
